[57] CLAIM

The ornamental design for a building element for a toy
building set, as shown and described.

DESCRIPTION

FIG. 1 is a top perspective view of the building element
for a toy building set showing our new design;
FIG. 2 is a bottom perspective view thereof;
FIG. 3 is a right side elevational view thereof;
FIG. 4 is a front elevational view thereof;
FIG. 5 is a left side elevational view thereof;
FIG. 6 is a rear elevational view thereof;
FIG. 7 is a top plan view thereof;
FIG. 8 is a bottom plan view thereof; and,
FIG. 9 is a partial view of the top of the building ele-
ment, shown separately for ease of illustration only.
